UNITED STATES PATENT OFFICE.

HAROLD J. POWER, OF SOMERVILLE, MASSACHUSETTS, ASSIGNOR TO AMERICAN RADIO & RESEARCH CORPORATION, OF MEDFORD, MASSACHUSETTS, A CORPORATION OF DELAWARE.

INDUCTANCE DEVICE.

Application filed March 11, 1918. Serial No. 221,641.

To all whom it may concern:

Be it known that I, HAROLD J. POWER, a citizen of the United States, residing at Somerville, in the county of Middlesex and State of Massachusetts, have invented a new and useful Improvement in Inductance Devices, of which the following is a specification.

In certain electrical current-carrying instrumentalities of which inductance devices furnish an example, and especially those employed in connection with such high frequency currents as are present in wireless or radio installations, it is important to prevent the loss of energy from the conductors through their insulating supports, and to so compactly arrange the devices that little space is occupied and, further, so that two or more of the devices may be brought into close relation to produce a mutual effect. These results are obtained by the present invention, which is here disclosed as embodied in an inductance spiral for radio work, though obviously its novel features may be otherwise utilized.

In the accompanying drawing—

Fig. 1 is a top plan view of an inductance device arranged in accordance with my invention, and

Fig. 2 is an enlarged vertical section on the line 2—2 of Fig. 1.

At 10 and 11 are shown inner and outer supporting members of any suitable insulating material. As illustrated, these members are in the form of rings of rectangular cross section, they being concentrically arranged and having through their walls, midway between the upper and lower sides, radial openings 12 which are preferably equally spaced about the rings and which may be brought into alignment. Between the rings, enclosed in the narrow supporting and protecting frame furnished thereby, is a conductor 13, in the present instance consisting of a spiral ribbon extending in regular, uniformly separated convolutions from its inner extremity 14 to the outer end 15 to form a flat pancake type of spiral, at which points 14 and 15 connection may be made to the external circuit. Between the edges of the ribbon, preferably midway, are openings 16 alined with one another radially and with corresponding openings 12 in the insulating rings 10 and 11, the radial series

of openings being here shown as separated by angles of 30°. Through the openings 12 and 16 extend carrier members furnished by rods 17 of insulating material, which may be retained in place by the engagement of the edges of the openings 16 in the spiral. Mounted upon the rods between the convolutions of the conductor are insulating separating members 18, conveniently in the form of thimbles surrounding the rods, there being one of these members 18 between each of the adjacent pairs of convolutions of the spiral and also between the inner and outer turns and the insulating rings. These thimbles space the turns of the spiral to keep them out of contact with one another and to maintain them in symmetrical relation. The parts of the device may readily be assembled by inserting the rods 17 through the openings, successively bringing the thimbles into position between the convolutions of the spiral so that the rods will pass through them. If desired, the thimbles may be cemented to the rods by means of an insulating varnish, this also excluding air and tending to produce a uniform supporting dielectric.

It will be obvious that the entire device, including both the conductor and its insulating supports, is comprised in a narrow space, so that it takes up little room in the contracted quarters commonly provided for radio apparatus; and that, moreover, a plurality of these devices may be placed with their rings one above the other, with the planes of the spirals parallel and in close proximity. This produces in a most effective manner, both as to distance and relation, a mutual inductive action to aid self inductance in producing the desired total inductance. With high radio frequencies the current in the conductor of the form illustrated flows almost wholly at the edges of the ribbon. Consequently the supporting dielectric, which at best may be of imperfect insulating properties, is in contact with the conductor at points outside the current path so that the loss by leakage is small, and the portion of the conductor outside the openings 16, which carries the current, is uniform in cross section and in resistance. Moreover, the separation between the current path and the supporting dielectric tends to minimize the loss of energy through

strains in the latter set up by the rapidly reversing field generated by the high frequency current.

I claim:

5 6. In an inductance device, a spiral conducting ribbon, and an insulating and supporting member situated wholly between the edges of the conductor ribbon.

7. In an inductance device, a spiral conductor provided with openings between its edges, and a supporting member extending through said openings from the inner to the outer convolutions.

8. In an inductance device, a spiral conductor provided with aligned openings, and an insulating carrier member extending through said openings from the inner to the outer convolutions.

9. In an inductance device, a spiral conductor provided with aligned openings, an insulating carrier member extending through said openings, and insulating means for separating portions of the conductor from one another at the aligned openings.

10. In an inductance device, a spiral conductor provided with openings, an insulating carrier member extending through said openings, and insulating means mounted upon the carrier member for separating portions of the conductor from one another.

11. A spiral conductor provided with openings in successive convolutions from the outer to the inner, and an insulating member extending through said openings.

12. A spiral conductor provided with openings in adjacent convolutions, an insulating member co-operating with the openings, and an insulating separating member between said adjacent convolutions.

13. A spiral conductor provided with openings in successive convolutions from the outer to the inner, an insulating member extending through said openings and beyond the conductor, and insulating members situated inside and outside the spiral and being engaged by the first-mentioned insulating members.

14. A spiral conductor provided with aligned openings in successive convolutions from the outer to the inner, an insulating member extending through said aligned openings, and a separator of insulating material mounted upon the carrier member in each space between the adjacent convolutions.

15. 10. A spiral conducting ribbon provided with aligned openings between its edges in adjacent convolutions, an insulating rod ex-

tending between the openings, and insulating thimbles surrounding the rod between the convolutions.

30

16. An inductance device comprising concentric insulating rings, radial insulating rods connecting the rings, and a spiral conducting ribbon lying between the rings and having aligned openings between its edges 35 through which the rods extend.

17. An inductance device comprising concentric insulating rings, radial insulating rods connecting the rings, a spiral conducting ribbon lying between the rings and having aligned openings between its edges 75 through which the rods extend, and insulating thimbles surrounding the rods between the convolutions of the spiral.

18. An inductance device comprising a flat 75 spiral conducting ribbon adapted to receive high frequency alternations, and connector means for preserving the spaced relation of the convolutions of the ribbon located between the opposite outer edges of the convolutions.

19. An inductance device comprising a flat or pancake form of spiral conducting ribbon adapted to receive high frequency alternations, and a radial connector rod located 25 between the opposite outer edges of the convolutions of the ribbon.

20. An inductance device comprising a flat or pancake form of spiral conductor ribbon adapted to receive high frequency alternations, and a connector rod passing 90 through openings formed in the convolutions of the spiral between the opposed outer edges.

21. An inductance device comprising a flat spiral of conducting ribbon adapted for the reception of high frequency alternations and a supporting dielectric between the convolutions engaging the ribbon between the opposite edges and at a substantial distance inside said edges to place the dielectric 100 outside the path of greatest current flow.

22. In a device of the kind described, a support of insulating material, a spiral inductance coil secured at its center to the 105 said support, the edges of the said coil being exposed upon each side of the support.

Signed at Somerville, in the county of Middlesex, and State of Massachusetts, this first day of March, 1918.

HAROLD J. POWER.
